(57) **CLAIM**

The ornamental design for a light saber toy, as shown and described.

DESCRIPTION

FIG. 1 is a first perspective view of a light saber toy showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of FIG. 7;

FIG. 10 is an enlarged view of FIG. 8;

FIG. 11 is an enlarged view of an encircle portion 11 in FIG. 1; and,

FIG. 12 is an enlarged view of an encircle portion 12 in FIG. 2.

The broken lines in the Figures are for the purpose of illustrating portions of the article that form no part of the claimed design. The dash-broken lines encircling portions of the claimed design that are illustrated in enlargements form no part of the claimed design.

1 Claim, 12 Drawing Sheets
